DUPLICATING MACHINE

Einar K. Johansen, Chicago, Ill., assignor, by
mesne assignments, to Clearing Machine Cor-
poration, Chicago, Ill., a corporation of Illinois

Application May 14, 1934, Serial No. 725,460

8 Claims. (Cl. 90—13.5)

This invention relates to improvements in duplicating machines of the type in which the cutter as well as the feeding of the work to the cutter is controlled by a tracer adapted to follow the profiles of a relatively soft pattern, and although operating against such soft pattern, is designed to control relatively heavy pressure, and in turn relatively heavy cutting machinery.

Still more specifically the invention relates to 10 a type of machine generally known and designated as a vertical knee column milling machine, in which the work supporting table as well as the pattern support are respectively advanced toward the cutter tool and the tracer by hydraulically operated means, the movements of the work and pattern in both a forward and backward direction, with respect to the tools, being automatically controlled by the action of the tracer against the pattern.

20 A further object is to provide an improved, simple and relatively inexpensive attachment of this character which may be readily applied to a milling machine of the type referred to, and thus provide an efficient machine for producing or duplicating an article from an inexpensive pattern or master.

25 A further object is to provide improved safety mechanism which will operate automatically to protect the machine and parts therefrom from injury, due to carelessness or neglect of the operator, and improved means for controlling the advancing movement of the work and pattern carrying supports, at the will of the operator.

To the attainment of these ends and the accomplishment of other new and useful objects 35 as will appear, the invention consists in the features of novelty in substantially the construction, combination and arrangement of the several parts hereinafter more fully described and 40 claimed and shown in the accompanying drawings illustrating this invention and in which

Figure 1 is a side elevation of a machine of this character constructed in accordance with the principles of this invention.

45 Figure 1^a is a detail view in elevation, on an enlarged scale, of the tracer.

Figure 2 is an elevation taken from the left hand side of Figure 1.

50 Figure 2^a is an enlarged detail view of the tracer, supporting means therefor and the adjusting mechanism.

Figure 3 is an enlarged detail sectional view taken on line 3—3, Figure 2.

55 Figure 4 is a detail sectional view taken on line 4—4, Figure 3.

Figure 5 is an enlarged detail sectional view taken on line 5—5, Figure 1.

Figure 6 is a detail sectional view taken on line 6—6, Figure 5.

Figure 7 is a detail elevation, taken on line 5 10—7, Figure 5.

Figure 8 is an enlarged detail, vertical, sectional view, showing the manner of converting the usual telescoping feeding knee screw and nut into a sliding connection.

Figure 9 is a detail vertical sectional view, on an enlarged scale, taken on line 9—9, Figure 1.

Referring more particularly to the drawings, the numeral 15 designates a supporting base upon which is mounted the standard 16, provided 15 with the usual knee 17 and spindle head or bearing 18, which latter is maintained in a fixed position upon the standard 16. The cutting tool 19 is secured to the spindle and the latter is rotated in any desired or suitable manner.

20 Mounted upon the knee 17 is the usual cross slide 20, and carried by the cross slide 20 is a work supporting table 21, the slide and table being reciprocated transversely with respect to each other in the usual manner.

25 The numerals 22 and 23 (see particularly Figure 8) designate the usual telescoping knee screw and nut which are usually employed for raising and lowering the knee, and which passes into the knee bearing 24 for raising and lowering the 30 knee. In the present invention these elements are converted into a sliding bearing, and to that end there is provided a sleeve 25 which replaces the ordinary knee screw nut, and is threaded upon the screw element 23. This element 25 35 telescopes into a sleeve 26 and is held against rotation with respect thereto by means of suitable fastening devices, such as pins 27, or the like. The sleeve 26 slides in the knee bearing 24 as the 40 knee is raised and lowered.

The base 15 (see particularly Figure 9) is cored out as at 28 to receive the ends of cylinders 29, two of such cylinders being disclosed in the present invention. Within each of the cylinders a piston 30 is reciprocable, and connected to each 45 of the pistons is a piston rod 31, which projects through the top of the cylinder and is secured to an arm or bracket 32 carried by the knee 17 so that when the piston 30 is raised, the knee 17 will be raised, and as the piston 30 descends 50 the knee 17 will also descend.

Hydraulic means are provided for raising the pistons 30, and to that end there may be provided a suitable pump 33, the inlet side of which 55 has communication with a liquid tank or reser-

voir 34 by means of a pipe connection 35. Leading from the outlet side of the pump is a pipe 36 which is connected with a branch pipe 37 that in turn is connected with passages 38 that lead to the bottom of each of the cylinders 29 beneath the piston 30, and leading from the top of each of the cylinders above the piston 30 is a passage 39 that communicates with a passage 40 with which a pipe 41 has communication, and which pipe 41 leads back to and discharges into the tank or reservoir 34, preferably adjacent the top thereof. With this part of the invention and when the pump 36 is operated, the liquid will flow from the pump through the pipe 37 into the cylinders 29 under the pistons 30 to raise the latter, and any liquid in the cylinders above the pistons 30 will be discharged through the passages 38-40 and pipe 41, back to the tank.

The raising movement of the pistons 30 and consequently the knee 17 is controlled by a tracer which is adapted to follow the contours and profiles of a pattern 42, which is mounted upon a support 43, preferably in the form of a platform or bracket secured to the table 21 of the machine, to be raised and lowered with the knee 17.

The tracer consists essentially of a casing or housing 44 having a chamber 45 therein (see particularly Figure 3) and in which chamber is arranged a sleeve 46 contacting with the wall thereof. In the wall of the sleeve 46 is a channel 47 extending therearound and openings or passages 48 are also provided through the sleeve which communicate with the channel 47 and also with the channel 49 in the wall of the casing or housing 44, and with which channel 49 a passage 50 communicates. A pressure pipe 51 communicates with the passage 50 and this pressure pipe 51 is connected and has communication with the pipe 37 as at 52, and is adapted to receive liquid under pressure from the pump 33.

Within the wall of the casing 44 is another channel or passage 53 which is spaced from and normally out of communication with the passage 49, and this passage 53 has communication with an opening 54 through the sleeve 46, with an exhaust pipe 55 that leads back to and discharges into the tank or reservoir 34. A slideable valve member 56, which is preferably hollow for the sake of lightness, slides within the sleeve 46 and is provided with a circumferential recess or channel 57 opening through the periphery thereof. This recess or channel 57 is adapted to be moved, in a manner to be described, so as to establish or cut off communication between the channels 47 and 53 and consequently communication between the pressure supply pipe 51 and exhaust pipe 55.

The numeral 58 designates the finger or stylus of the tracer and is provided with a head 59 which is disposed within the casing or barrel 46, the head being preferably in the form of a disc having an upwardly projecting circumferential flange 60. This head is held within the barrel or casing by means of a member 61 threaded into the open end of the casing 44 and held in adjusted position, if desired, by a lock nut 62. The member 61 is hollow as at 63 and is provided with a tubular portion 64 through which a shank 65 constituting a part of the stylus freely passes. The diameter of the shank 65 is considerably less than the internal diameter of the tubular portion 64 so as to allow the stylus 58-65 and the head 59 to rock within the barrel or casing 46. Means, such as a pin 66, carried by the valve member 56 and 75 extending into a slot 67 in the head 59 of the

stylus is provided for maintaining the valve member 56 and the stylus member against axial rotation one with relation to the other.

Leading through the end member 61 are passageways 68 having communication with the hollow portion 63 of the end member, and these passageways discharge into a cup or receptacle 69 from which a drain pipe 70 leads, and which drain pipe communicates with the tank or reservoir 34 so that, if during the operation of the tracer or at any time any liquid should find its way past the end of the valve 56 and past the head 59 of the tracer into the cavity or open space 63, it will flow therefrom into the receptacle 69 and be discharged back into the tank or reservoir 34.

The tracer, as well as the valve member 56, are held in their forward positions, that is, so that the passage 47 will be closed to the pressure pipe 51, and the passage 53 will be open to the exhaust pipe 55, or in the position shown in Figure 3, by means of a spring 71 which is arranged within a barrel or tubular portion 72 which forms an extension or portion of the other end member 73 of the casing 44, and which member 73 is secured in position by being threaded into the open end of the casing 44.

A rod 74 is secured by one end as at 75 to the end of the valve 56 and projects through the top member 73 for any desired distance, and also 30 through the spring 71, so that one end of the spring will rest against the end of the valve member and the other end of the spring will rest against the extremity of a tubular element 76, and which element is threaded through the member 73. The element 76 may be provided with a head 77 which is knurled, and a lock nut 78 may be provided for locking the member 76 in its adjusted position. By the provision of this member 76, it will be manifest that the stress of the spring 40 71 may be varied, and thereby the pressure against which the stylus or finger is operated may be varied.

The valve 56 is provided with an opening 79 in one end thereof through which the tubular 45 member 72 passes and is of a diameter considerably greater than the diameter of the tubular member so as not to interfere with the operation of the parts.

Assuming the parts to be in the position shown 50 in Figure 3, and with the end of the stylus or finger 58 out of contact with the pattern 42, the valve 56 will be in the limit of its forward movement so that communication between the pressure supply pipe 51 and the exhaust pipe 55 will be cut 55 off, with the result that when the pump 33 is operating, liquid will be forced by the pump (see Figures 1, 3 and 9) through the pipe 36, pipe 37, passage 38, under the piston 30 to raise the latter. At the same time a portion of the liquid discharged by the pump will be forced through the pipe 51 into the passages 50, 49 and 47, but as the passage 47 constituting the outlet within the casing 44 of the tracer, is closed, the pressure exerted by the pump will be built up under the piston 30, 65 with the result that the knee of the machine will be raised until the work 39 is brought into contact with the cutter 49, which will occur at substantially the same time that the pattern 42 is brought into contact with the stylus or finger 58.

As soon as the stylus or finger 58 is moved by the pattern 42, the head 59 will move the valve 56 backwardly against the stress of the spring 71 and this will establish communication between the passages 47, 53, 54 and exhaust pipe 55, there- 75

by relieving the pressure under the pistons 30, so that the upward movement of the piston 30 and knee 17 will be arrested during the operation of the cutter upon the work and the traversing of the stylus over the pattern 42.

Any irregularities in the pattern will cause a corresponding movement of the stylus 58 and consequently the valve 56, and this will control the extent or degree of raising movement of the knee. The amount of pressure exerted upon the piston 38 will then be controlled by the degree or size of the opening forming communication between the passages 48 and 58.

As the piston 30 rises, any liquid which is in the cylinder 29 above the piston, will be discharged through the passage 39 (see Figure 9), passage 40, pipe 41, back to the tank or reservoir 34.

The operation of the stylus or finger 58, which in turn operates the valve 56, will control the raising and lowering movement of the knee, the lowering movement being effected by gravity.

In order to prevent the building up of excess pressure by the pump 36 beneath the pistons 30, a pressure regulating valve of any desired type, diagrammatically indicated by the reference character 81, may be provided in the pipe 36 between the pump and the connection 52 of the pipe 51 with the pipe 36, and a control valve 82 may also be provided in the pipe 36.

In order to prevent undesired operation and the sucking of the liquid above the pistons 30 when the knee descends, there may be provided a vent 83 in the tank or reservoir 34 above the liquid level.

Obviously, during the operation of the cutter upon the work, the cross slide 20 and table 21 are given reciprocatory movements in the manner usual in milling machines of this character.

The tracer mechanism may be supported in any suitable manner, such as by means of an arm or bracket 84 secured to the standard 16 and having a bearing 85 therein in which a stem 86 is mounted, and which stem is adjustable vertically by means of an adjusting wheel or member 87 that engages a threaded portion 88 of the stem, a gage 89 being provided, if desired, for indicating the adjustment.

The stem is provided with a laterally projecting bearing member 90 having a slide 91 (see Figures 2 and 2^a) movable therein, and the slide is provided with keys or ways 92 to prevent rotation in the bearing. The bearing is split and is provided with a clamping member 93 so as to secure the parts in adjusted position. A screw 94 is threaded into a seat 95 in the bearing 90 and the screw passes through a loop or flange 96 on the slide so that when the handle 97 is operated the bearing member 91 may be adjusted transversely with respect to the stem 86.

A slide 98 is arranged transversely of the bearing member 91 and is adapted to be adjusted by means of a hand wheel or screw 99 and the slide is held in its adjusted position by means of screws 100 passing through slots in the bearing member and into the slide. Obviously, any other form of adjustment of these parts may be provided. The slide 98 is provided with a semi-circular bearing 101, which encompasses a portion of the housing or casing 44 of the stylus. Another semi-circular member 102 encompasses the other portion of the housing 44, and these parts are secured together by means of fastening screws 103.

Thus it will be manifest that a vertical adjustment of the tracer casing 44 may be obtained by

actuation of the hand wheel 87, while a transverse and longitudinal movement of the tracer casing 44 may be had through the adjustment or operation of the hand wheels 87-89.

It sometimes happens that through carelessness or for other reasons, it is desired to arrest the upward movement of the knee of the machine at a predetermined point in its movement to prevent injury to parts of the machine, and therefore a safety mechanism for that purpose may be employed.

A simple and efficient means for accomplishing this result comprises a vertically arranged rod or bar 104 (see particularly Figures 1 and 2) which is secured to the knee 17 and is vertically adjustable with respect thereto. Arranged within the path of movement of the end of the rod 104 and supported preferably by the arm 84 is a rack member 105, having a head 106, and which member moves in a casing 107. The casing is provided with an opening 108 through which a gear wheel 109 projects to engage the teeth of the rack 105.

A spring 110 is arranged in the casing 107 and operates upon the rack member 105, tending normally to lower the head 106 into the path of the upward movement of the end of the rod 104. The shaft 111 of the gear wheel 109 is connected by means of a swivel joint 112 to a rod or member comprising telescoping sections 113. At the forward end of the rod 113 a section 114 is connected by means of a universal joint 115, and this member 114 is journaled in a suitable bearing 116. On the end of the member 114 is arranged a cam or eccentric 117 which engages a pivotally mounted rocker member 118. The end of this rocker member 118 is preferably bifurcated to stand astride of the rod 74 which is connected to the valve 56 (see Figure 3), adjustable nuts or collars 119 being secured to the end of the rod. When the knee of the machine is in a position that the end of the rod 104 is out of contact with the head 106 of the rack member 105, the cam 117 will be in a position so that the rocker member 118 will be inactive with respect to the rod 74, and the spring 110 will force the rack member 105 downwardly. As soon as the end of the rod 104 engages the head 106 of the rack member 105, a further raising movement of the knee will cause the rack 105 to be raised, thereby rotating the gear 109 and with it the shaft or rod 113. This will rotate the cam member 117 and the same will act against the rocker member 118, causing the latter to raise the rod 74 and with it the valve 56, thereby establishing communication between the passage 47 (Figure 3) of the tracer valve and the passage 53, so as to relieve the pressure of the pump in the cylinders 29 as the liquid will flow through the pipe 51, into the passage 47 and thence into the passage 53, through the exhaust pipe 55, back to the tank. As soon as the knee is lowered sufficiently to permit the rack 105 to be lowered under the stress of the spring 110 a sufficient distance the cam 117 will allow the valve 56 to move to the position shown in Figure 3.

If desired a manual means may be provided for similarly controlling the upward movement of the knee 17. To that end there may be provided a member 120 (see particularly Figure 5) having a cam surface 121, mounted to slide in suitable bearings and through the casing 107. To this end of this member 120 is connected a handle 122 in a suitable position for the operator. Mounted upon the rack member 105 is a

roller 123 which is adapted to be contacted by the cam face 121 so as to raise the rack member 105 against the stress of the spring 110 when the handle 122 is moved in one direction, resulting in the rotation of the shaft 111. As soon as the handle 122 is moved in the opposite direction, the spring 110 will return the rack member 105. Another mechanical safety device may be provided for controlling the movement of the knee, 10 by manipulation of the tracer finger or stylus and this may be accomplished by providing a handle or lever 124 pivotally mounted intermediate its ends as at 125, and on which handle or bar may be provided a cam portion 126 so arranged 15 that when the handle 124 is moved about its pivot in one direction, the cam 126 will contact the side of the shank 65 of the stylus or finger member and move the same laterally, thereby causing a rocking movement of the head 58 within 20 the barrel 48. This movement will, through the medium of the flange 60 on the head 58, move the valve member 56 back against the stress of the spring 71 (see Figure 3) to relieve the pressure in the cylinders 29 by connecting the passages 51 and 55.

It is thought that the operation of this device will be clearly understood from the foregoing, but briefly stated, it is as follows.

When the stylus or finger 58 of the tracer is 30 out of contact with the pattern 42, the spring 71 will hold the valve 56 at the limit of its forward movement so that communication between the pressure supply passage 51 and the pressure exhaust passage 55 will be closed or cut off. When 35 the pump 33 then operates, liquid will be forced under pressure to the bottom of the cylinders 29 and beneath the pistons 30 through the pipe 37, and at the same time some of the liquid will be forced through the pipe 51 into the tracer casing 40 or cylinder 44 but, as communication between the pressure supply pipe 51 and the exhaust pipe 55 will be cut off by reason of the position of the valve 56 (see Figure 3) the pump will continue 45 to build up pressure under the pistons 30, and the knee and the supported work and pattern will be raised. Any liquid above the piston will be discharged from the top of the cylinder through the passage 39 and pipe 41, back to the tank or reservoir 34.

50 Any excess pressure will escape through the pressure controlled valve 80 back to the tank or reservoir 34.

As soon as the end of the finger or stylus 58 contacts with the pattern 42, the valve 56 will 55 be bodily shifted from the position shown in Figure 3 and into a position that communication will be established between the pressure supply pipe 51 and the exhaust pipe 55 so as to relieve the pressure in the cylinders 29 and thereby control 60 the raising movement of the knee.

As the stylus or finger 58 follows the contour or profiles of the pattern, the knee 17 will be correspondingly raised and lowered, the lowering movement being effected by gravity.

65 At the same time, the cross slide and table 20—21 will be given reciprocating movement to move the work longitudinally and laterally, in a manner well known in this art.

Should the knee be raised to an undesired 70 height before the stylus 58 contacts with the pattern, the end of the rod 104 will contact the rack member 105 and the valve 56 will then be moved against the stress of the spring 71 to establish communication between the pressure supply pipe 75 and the exhaust.

If it is desired to arrest the raising movement of the knee at any time during the operation of the machine, this may be accomplished through the medium of the control handle 122 or the control handle or lever 124.

With this improved construction the work and pattern are moved respectively toward the cutting tool and the stylus of the tracer and there is provided means for automatically controlling and regulating the extent of raising and lowering movement of the knee, and at the same time this control will be automatically effected through the operation of the tracer upon the pattern.

It will also be manifest that there is provided 15 a comparatively simple and inexpensive attachment which may be readily applied to a vertical knee column milling machine.

While the preferred form of the invention has been herein shown and described, it is to be 20 understood that various changes may be made in the details of construction and in the combination and arrangement of the several parts, within the scope of the claims, without departing 25 from the spirit of this invention.

What is claimed as new is:—

1. In a duplicating machine a slidable carriage for the work, a pattern support connected with the carriage, a cutter for the work, a tracer for the pattern, both said cutter and tracer mounted 30 in fixed positions, an hydraulic system embodying means for circulating a fluid medium under pressure for moving said carriage in a plane transverse to the plane of sliding movement thereof to bring the work and pattern respectively up to 35 the cutter and tracer, means embodying a valve responsive in its operation to the action of the tracer upon the pattern, for controlling the pressure of the fluid medium and thereby control the movement of the carriage under the effect of such fluid pressure, and additional means operating automatically by the movement of the carriage past a predetermined point in the path of movement of the carriage under such fluid pressure, for also actuating said valve to reduce 40 such pressure. 45

2. In a duplicating machine, a work cutter mounted in a fixed position, a reciprocable work holder, a piston operatively connected with said holder, a cylinder containing the piston, a pipe line communicating at one end with the cylinder, 50 a valve for controlling the other end of the pipe line, a fluid pump connected in the pipe line imposing pressure on the piston to keep the work against the cutter, a pattern tracer which is subject to vibration by the profile of a pattern to 55 variably open the valve and cause variable drops of pressure in the pipe line, and additional means a portion of which is arranged in the path of movement of the work towards the cutter under such pressure to be engaged and shifted by the 60 work holder for opening said valve.

3. In a duplicating machine, a work cutter mounted in a fixed position, a reciprocable work holder, a piston operatively connected with said holder, a cylinder containing the piston, a pipe 65 line communicating at one end with the cylinder, a valve for controlling the other end of the pipe line, a fluid pump connected in the pipe line imposing pressure on the piston to keep the 70 work against the cutter, a pattern tracer which is subject to vibration by the profile of a pattern to 75 variably open the valve and cause variable drops of pressure in the pipe line, supporting means for the tracer, a hand lever pivotally 75

mounted intermediate its ends, and a cam on one end of the lever adjacent the pattern tracer, said cam upon movement of the lever about its pivot engaging the side of the tracer shank to shift the latter to move the said valve.

5. In a duplicating machine, a tracer and a cutter, mounted in fixed position, a support for the work and a master, means against which fluid pressure is expended to push the said support toward the cutter and tracer and for holding the work and pattern respectively in contact with the cutter and tracer, means embodying a valve variously operated by the tracer as the latter follows the profile of the pattern to vary the effective fluid pressure, means, a portion of which, is arranged in the path of movement of the work to the cutter to be engaged and shifted by the work holder to vary the effective fluid pressure, and means controllable at will and operable upon a portion of the last recited means for also varying the effective fluid pressure.

5. In a duplicating machine, a rotatable cutter and a tracer mounted in fixed positions, a slideable carriage for the work and a master, an hydraulic system for moving the carriage in a plane transverse to the plane of its sliding movement to bring and hold the work and master respectively in contact with the cutter and tracer, said system embodying a cylinder, a piston in the cylinder and operatively connected with the carriage, fluid pressure creating means in the system, a valve at one end of the system, the master engaging element of the tracer operating when vibrated by following the profile of the pattern to variably open the valve to cause variable drops in the system, and means for conveying back into said system any fluid which may leak past the said valve.

40. 6. In a duplicating machine, a tracer and a work cutter mounted in fixed positions, a support for the work and a master, means against which fluid pressure is expended to move said support towards the cutter and tracer and for holding the work and pattern respectively in contact with the cutter and tracer, means embodying a valve variously operated by the tracer as the latter follows the profile of the pattern to vary the effective fluid pressure, means arranged within the

path of movement of the said support in a direction toward the cutter for operating the valve to vary the effective fluid pressure, and manual means co-operating with the last recited means for also operating said valve at will and at any point in the path of movement of said support.

7. In a duplicating machine, a tracer and a work cutter mounted in fixed positions, a support for the work and a master, means against which fluid pressure is expended to move said support towards the cutter and tracer and for holding the work and pattern respectively in contact with the cutter and tracer, means embodying a valve variously operated by the tracer as the latter follows the profile of the pattern to vary the effective fluid pressure, means arranged within the path of movement of the said support in a direction toward the cutter for operating the valve to vary the effective fluid pressure, manual means co-operating with the last recited means for also operating said valve at will and at any point in the path of movement of said support, and an additional manual means operable at will and upon said tracer for also operating said valve.

8. In a duplicating machine, a slideable carriage for the work, a pattern support connected with the carriage, a cutter for the work, a tracer for the pattern, both said cutter and tracer mounted in fixed positions, an hydraulic system embodying means for circulating a fluid medium under pressure for moving said carriage in a plane transverse to the plane of sliding movement thereof to bring the work and pattern respectively up to the cutter and tracer, means embodying a valve responsive in its operation to the action of the tracer upon the pattern, for controlling the pressure of the fluid medium and thereby control the movement of the carriage under the effect of such fluid pressure, additional means operating automatically by the movement of the carriage past a predetermined point in the path of movement of the carriage under such fluid pressure for also actuating said valve to reduce said pressure, and a manually operable device co-acting with the last said means for also actuating said valve at any time in the cycle of operation of the machine.

EINAR K. JOHANSEN.
